UNITED STATES PATENT OFFICE

156,979

COMBINED HANDBAG AND MUFF

Louis Lipshutz, New York, N. Y.

Application June 16, 1948, Serial No. 147,014

Term of patent 3½ years

(Cl. D87—3)

To all whom it may concern:

Be it known that I, Louis Lipshutz, a citizen of the United States, residing at New York, in the county of New York and State of New York, have invented a new, original, and ornamental Design for a Combined Handbag and Muff, of which the following is a specification, reference being had to the accompanying drawing, forming a part thereof.

In the drawing:

Fig. 1 is a front perspective view of a combined handbag and muff showing my new design, portions of the strap element being broken away for convenience of illustration;

Fig. 2 is a rear perspective view of the combined handbag and muff with the strap element omitted;

Fig. 3 is a top plan view thereof as shown in Fig. 2 with the handbag portion in an open position;

Fig. 4 is an enlarged front elevational view of the same.

I claim:

The ornamental design for a combined handbag and muff, as shown.

LOUIS LIPSHUTZ.
